UNITED STATES PATENT OFFICE.

NEWTON CRANE, OF NEWTON, MASSACHUSETTS.

DESIGN FOR A FASTENING MEMBER.

SPECIFICATION forming part of Design No. 29,538, dated October 25, 1898.

Application filed September 29, 1898. Serial No. 092,234. Term of patent 7 years.

To all whom it may concern:

Be it known that I, NEWTON CRANE, of Newton, in the county of Middlesex and State of Massachusetts, have invented and produced a certain new and original Design for a Fastening Member, of which the following is a specification.

This invention relates to a new and original design for a member of a pair of fastening devices or clasps; and it consists in the novel features of shape and configuration hereinafter fully described and claimed and clearly illustrated upon the accompanying drawings.

15 Of the drawings, Figure 1 represents in perspective view a clasp or fastening member embodying my design. Fig. 2 represents a section through the same on the line 2 2 of

Fig. 1.

20 The article of manufacture embodying my design is shown as a plate having the minor portion a thereof bent at an inclination to the

major portion a' . It has two parallel edges $a^2 a^3$, to which the end a^{10} is at right angles. The edges $a^2 a^3$ are curved outward, as at $a^4 a^5$, 25 and then inward until they meet the straight edge a^6 , which is parallel to the edge a^4 . A slot a^7 , having parallel side walls and curved end walls, is formed in the swelled portion of the plate. There is another aperture a^8 30 formed between the slot a^7 and the inclined portion a , said aperture being substantially rectangular, except for the reentrant projection a^9 , as shown in Fig. 2.

I claim—

The design for a fastener or clasp member, substantially as shown and described.

In testimony whereof I have affixed my signature in presence of two witnesses.

NEWTON CRANE.

Witnesses:

MARCUS B. MAY,
C. C. STECHER.
